UNITED STATES PATENT OFFICE.

AUGUSTUS RENTZ STEVENS, OF TAMPA, FLORIDA, ASSIGNOR OF ONE-HALF TO
J. S. LONG.

FRUIT-SIZER.

1,095,941.

Specification of Letters Patent.

Patented May 5, 1914.

Application filed August 29, 1913. Serial No. 787,299.

To all whom it may concern:

Be it known that I, AUGUSTUS R. STEVENS, a citizen of the United States, and a resident of Tampa, in the county of Hillsboro and State of Florida, have made certain new and useful Improvements in Fruit-Sizers, of which the following is a specification.

My invention relates to improvements in fruit sizers, and it consists in the combinations, constructions, and arrangements herein described and claimed.

An object of my invention is to provide a device by means of which fruit may be graded into sizes according to the largest diameter of the fruit.

A further object of my invention is to provide a fruit sizer having means for adjusting the parts of the sizer so as to vary the sizes of the fruit deposited at any one point.

Other objects and advantages will appear in the following specification and the novel features of the device will be particularly pointed out in the appended claims.

My invention is illustrated in the accompanying drawings forming part of this application in which similar reference characters indicate like parts in the several views, and in which—

Figure 1 is a plan view of the device, Fig. 2 is a side view thereof, Fig. 3 is a section along the line 3—3 of Fig. 1, Fig. 4 is an end view of the device showing a modified form of roller, Fig. 5 is a section along the line 5—5 of Fig. 1, Fig. 6 is a section through one end of the device, Fig. 7 is a perspective view of one of the track rails, and Fig. 8 is a plan view of a portion of the track on an enlarged scale.

In carrying out my invention I make use of a frame consisting of the uprights 1 the upper and lower cross members 2, and the longitudinal members 3.

On the lower cross member 2 are secured longitudinal supports 4 for track rails 5. The latter are preferably composed of pieces of hard wood which are beveled at their upper edges. As will be seen from Fig. 3 the upper cross member 2 bears longitudinal side members 6, against which the track rests 7 abut. The members 6 and 7 are held in place by means of a slotted bracket 8 which is adjustably secured by a bolt 9. At the center of the device is a support 10.

A central track rail 11 is carried by the support 10.

In Figs. 7 and 8, I have shown the upper track rails. These consist of sections 12, each of which is secured to a backing 13. 60 Bolts 14 pass through the backing 13 and also through the side members 6. The latter is recessed and is provided with a spiral spring 15 which is arranged to bear on a nut 16 carried by each of the bolts 14. A 65 plate or washer 17 is secured to the outer side of the member 6. This construction permits the adjustment of the track rail sections 12 toward or away from each other, since by turning on the nut 16 the rail may 70 be drawn outwardly, while when turning the nut in the opposite direction the spring 15 which also holds the nut against the plate 17 will thereby force the rails toward each other.

The track sections are preferably about 24" long but may be of greater or less length if desirable. The track sections are placed parallel with each other but each successive section is offset slightly, preferably an 80 eighth of an inch. The ends of each of the track sections are beveled as shown at 12^x, those of one section being beveled on the inside and of the adjacent section being beveled on the outside to prevent the rolls 85 from jumping the track. In view of the fact that the successive sections are each offset so as to be farther away from the central axis of the machine, the effect is to provide a device having a track whose rails 90 are closer together at one end than at the other. The divergence of these rails is shown in Fig. 1.

At intervals I make use of Z-shaped suspending members 18 which bear angle irons 19, the latter serving as guides for endless chains 20. To every other link of the chains 20 is secured a cross rod 21. These cross rods each bear a rotatable ball-shaped roller 22, provided with a groove 22^x arranged to 100 run on the track 11 and outside rollers 23 having grooves 23^x arranged to run on the track rails 12. Each of the rollers 23 is provided with an inner hemispherical surface. The outer rollers are provided with 105 suitable bearing members, such as those shown at 23^y.

Disposed transversely of the longitudinal frame members 3 at the ends of the machine are the shafts 24 which are mounted on bear- 110

ings 25 carried by the members 3. One of the shafts bears a drive pulley 26. These shafts are provided with sprocket wheels 27 arranged to receive the chains 20. Secured to the uprights 1 are guide members 28 (see Fig. 3) arranged to receive and guide the chains 20 on their return.

Disposed longitudinally of the device is a rod 29 which supports a fabric 30 of canvas or similar material, the outer ends of the canvas being fastened to the sides 31. The latter form in fact the backs of bins (not shown). Running boards 32 are carried by extensions of the cross members 2.

15 From the foregoing description of the various parts of the device the operation thereof may be readily understood.

As will be seen from Fig. 1, the space between the outer rollers 23 and the central 20 rollers 22 is less at one end of the machine and is progressively greater toward the other end. The fruit enters the device at the end at which the rollers are nearer together. Power is applied to the pulley 26 25 and the endless carrier formed by the chains, the cross shafts 21, and the rollers, bears the fruit along. The rollers being in contact with the tracks rotate and this tends to turn the fruit so as to rotate it about its largest 30 diameter. When the outer rollers reach the ends of the sections, the two outer rollers which are loose on their shafts move outwardly, thus increasing the distance between the outer rollers and the inner rollers 22.

35 As soon as the fruit arrives at a point where the rollers will not support it further, it drops down upon the canvas or fabric sheet 30 and rolls into the proper bin. It is obvious that the smaller fruit will drop first.

40 Since the sections of track are parallel, it follows that no more than one size of fruit will fall through the space represented by each adjustable section of track, as would be the case if the sections were not arranged 45 in parallel relation. This insures the delivery of fruit of a given size at a given point.

I desire to call attention to the fact that it is of advantage to have the smaller fruit 50 drop first because it has been found that in other fruit-sizers where the large fruit is forced out first it will sometimes take with it some of the small fruit. In this device this is impossible since there is no crowding 55 of the fruit.

The provision of the means of spreading the tracks allows also of using the device with large as well as with small fruit, and thus the machine serves a double purpose.

60 I claim:

1. In a fruit sizing device, a frame, a series of central supporting members disposed longitudinally of the frame, a series of supporting members spaced from said central 65 series on each side of the latter, the distance

between the side series of supporting members and the central series being progressively greater from one end of the machine to the other, and means for moving said series of supporting members from one end of the machine toward the other. 70

2. In a fruit sizing device, a frame, a series of central supporting members disposed longitudinally of the frame, a series of supporting members spaced from said central 75 series on each side of the latter, the distance between the side series of supporting members and the central series being progressively greater from one end of the machine to the other, means for moving said series of supporting members from one end of the machine toward the other, and means for rotating each member of all of said series of supporting members during such movement. 80

3. In a fruit sizing device, a main frame, 85 a series of rollers carried by said main frame and movable longitudinally thereof, a series of rollers on each side of said central series, said last named rollers being movable longitudinally of the frame, the line of travel of said last named series of rollers being substantially oblique to the first named series. 90

4. In a fruit sizing device, a main frame, 95 a series of rollers carried by said main frame and movable longitudinally thereof, a series of rollers on each side of said central series, said last named rollers being movable longitudinally of the frame, the line of travel of said last named series of rollers being substantially oblique to the first named series, and the line of travel of one series of said side rollers being oblique to the line of travel of the other series of 100 said side rollers. 105

5. In a fruit sizing device, a frame, a pair of sprocket chains carried thereby, transverse rods carried by said sprocket chains, a central roller and side rollers carried by each rod, means for moving said chains, the distance between said side rollers and said central roller at one end of the machine being greater than at the other, a straight central track rail disposed below said central roller and arranged to be engaged thereby, and straight central track rails disposed below the side rollers for supporting the latter, each of said track rails serving to cause the rotation of the rollers during the passage 115 thereof. 120

6. In a fruit sizing device, a frame, a pair of sprocket chains carried thereby, transverse rods carried by said sprocket chains, a central roller and side rollers carried by each rod, means for moving said chains, the 125 distance between said side rollers and said central roller at one end of the machine being greater than at the other, a straight central track rail disposed below said central roller and arranged to be engaged thereby, 130

straight central track rails disposed below the side rollers for supporting the latter, each of said track rails serving to cause the rotation of the rollers during the passage therealong, and a resilient receiver disposed beneath said rollers.

7. In a fruit sizing device, a frame, a pair of sprocket chains carried thereby, transverse rods carried by said sprocket chains, a central roller and side rollers carried by each rod, means for moving said chains, the distance between said side rollers and said central roller at one end of the machine being greater than at the other, a straight central track rail disposed below said central roller and arranged to be engaged thereby, straight central track rails disposed below the side rollers for supporting the latter, each of said track rails serving to cause the rotation of the rollers during the passage therealong, and a resilient receiver disposed beneath said rollers, said resilient receiver being inclined downwardly from the center of the machine toward the outside thereof.

10 8. In a fruit sizing device, a frame, a pair of sprocket chains carried thereby, transverse rods carried by said sprocket chains, a central roller and side rollers carried by each rod, means for moving said chains, the distance between said side rollers and said central roller at one end of the machine being greater than at the other, a straight central track rail disposed below said central roller and arranged to be engaged thereby, straight central track rails disposed below the side rollers for supporting the latter, each of said track rails serving to cause the rotation of the rollers during the passage therealong, a resilient receiver disposed beneath said rollers, said resilient receiver being inclined downwardly from the center of the machine toward the outside thereof, and means for adjusting the angular relation of the outside track rails to that of the center track rail.

9. In a fruit sizing device, a frame, a central track rail mounted thereon, side track rails spaced from said central track rail, said side rails being inclined with respect to said central track rail from one end of the machine to the other, an endless carrier comprising a series of cross rods, a central roller and side rollers carried by each cross rod, said central roller being arranged to engage said central rail and said side rollers being arranged to engage their indi-

vidual side track rails, means for driving said endless carrier, and means for varying the angular relation of the side track rails with that of the center track rail.

60

10. In a fruit sizing device, a frame, a central track rail mounted thereon, side track rails spaced from said central track rail, said side rails being inclined with respect to said central track rail from one end of the machine to the other, an endless carrier comprising a series of cross rods, a central roller and side rollers carried by each cross rod, said central roller being arranged to engage said central rail and said side rollers being arranged to engage their individual side track rails, means for driving said endless carrier, means for varying the angular relation of the side track rails with that of the center track rail, said last named means comprising screw bolts arranged to pass through the side of the machine and secured to the base of said side track rails, and nuts for drawing up said screw bolts.

75

11. In a fruit sizer, a frame, a pair of endless chains carried by said frame, transverse rods carried by said endless chains, a series of rollers carried by said rods, a central rail for supporting and guiding said rollers, side rails parallel with said central rail, said side rails being composed of a plurality of sections, each successive section being offset from the adjacent section, and rollers carried by said rods and slideable therealong, said last named rollers being arranged to run upon and be guided by the rails which are made up of sections.

80

12. In a fruit sizing device, a frame, a pair of sprocket chains carried thereby, transverse rods carried by said sprocket chains, a central roller carried by each of said rods, an end roller carried by each of said rods on each side of said central roller, said end rollers being movable longitudinally of the rod, a central track for supporting and guiding said central roller, tracks for supporting and guiding said end rollers, each of said latter tracks being composed of a series of sections parallel with said central track rail, each section being offset from the adjacent section, and the ends of each section being beveled to prevent the roller from jumping the track.
